DEVICE FOR DRAWING METAL BARS

Jean R. Tschudnowsky, Paris, France, assignor
to Compagnie Generale du Duralumin et du
Cuivre, Paris, France, a corporation of France

Application November 29, 1950, Serial No. 198,083

5 Claims. (Cl. 205—24)

1

My invention relates to the drawing, usually cold, of metal pieces.

It is known that to facilitate the insertion into dies or draw plates of metal bars or other pieces, for the purpose of drawing them, the usual practice has been to first shape, as by tapering, one end which is called the tang.

It is known, for the purpose of accelerating the drawing operation, to have the drawing benches equipped with devices permitting the insertion of the metal bars or pieces to be drawn into the dies or draw plates by simple pushing, thus avoiding the preliminary step of shaping one end to form a tang.

The present invention relates to the arrangement of such drawing benches, and has for an object to still further increase their productive capacity.

Another object of the present invention is to provide a device for drawing metal bars or pieces without preliminary shaping thereof, wherein the pieces to be drawn are held in gripping jaws mounted on a movable head, and are pushed by force into the dies or draw plates, as by means of a horizontally sliding carriage which carries the head carrying the gripping jaws, this device being characterized by the fact that control means are provided for the purpose of causing, at the end of the return stroke of the gripping head to its initial position, the temporary raising of the gripping head for the insertion of new metal bars or pieces to be drawn, this latter operation being performed during the drawing of the metal pieces which had been previously inserted.

The means which may be used to thus raise the gripping head include a pneumatic jack with vertical thrust disposed at a position below the base of the machine, and the head of this jack may be elevated to engage the gripping head and push it upward when the gripping head is in a position over the jack.

The present invention will be understood from the following description by reference to the accompanying drawings, which show the apparatus mounted at one end of a drawing bench for the simultaneous drawing of three metal bars, and embodying the device according to the present invention, and in which drawings:

Fig. 1 is a longitudinal sectional view of the drawing apparatus at the moment when the pushing of the metal bars into the dies or draw plates has been terminated;

Fig. 2 is a view similar to Fig. 1, at the moment when, in the operation of drawing metal bars, the operator feeds to the drawing bench new metal bars to be drawn;

2

Fig. 3 is a view of the drawing bench in transverse section, taken on the plane III—III of Fig. 2;

Fig. 4 is a view of the drawing bench taken in section on the plane IV—IV of Fig. 3; and

Fig. 5 is a circuit diagram of the electric circuits for control of the drawing apparatus by electrically controlled valves of the pneumatic or hydraulic actuating devices and the connecting conduits.

Figs. 6 and 7 show for two different operating positions details of the stirrup and the locking bolt and its flange,

Fig. 8 is a detail in longitudinal section of the gripping head and control jack, and

Fig. 9 is a transverse section taken on the line IX—IX of Fig. 8.

Referring to the drawings, the apparatus is mounted on a base 8 which is rigidly connected to the support 9 supporting the drawing bench on which the die stock block is mounted. A die stock block is shown at 23, carrying dies 23a, 23a in the prolongation of the drawing bench.

Beneath the base 8 there is mounted a pump 1, which may be a hydraulic pump, and which is driven by an electric motor 2. The fluid output of pump 1 is delivered by pipes, which include control valves, to the two piston control cylinders or press pots 3 and 4 mounted on the base 8 on the respective sides of the remote end of the base; the two pistons 5 and 6 operating in these cylinders 3 and 4, push out or pull back a horizontally sliding carriage 7 which is guided along the length of the two lateral edges of base 8 by the two horizontal rails 24, 24, which are best shown in Fig. 3.

On the front part of this sliding carriage 7, there is fixedly mounted a vertical slide which slidably receives a gripping head 10 for gripping the metal bars 18 which are to be drawn, as shown in Figs. 3 and 4. This head 10 can slide vertically in a slide mounted on carriage 7, and, as shown, the jack 11, in this case, can cause this vertical movement of the head 10 when head 10 is in a position over jack 11, by pushing upwardly against head 10. The slide 7 with gripping head 10 and control jack 11 are shown in longitudinal section in Fig. 8, and in Fig. 9 are shown in transverse section taken on the plane IX—IX of Fig. 8.

The metal bars 18 to be drawn are gripped in the interior of the head 10 by sets of jaws 12 in the shape of wedges (Fig. 4), whose small ends are pointed in the direction opposite to the pushing movement of the sliding carriage 7. At the time of the gripping of the bars 18 to be

drawn, these jaws 12 are positioned wedged against the latter by the surfaces 10' of a corresponding slope of gripping head 10.

The unit for control of the gripping or the releasing of each of the sets of jaws 12 on the bars 18, is, for each bar, an individual pneumatic cylinder 13. In the operation of each of such cylinders 13, the wedge jaws 12 are fixed on a stirrup 14, which moves vertically with head 10 and which can be pushed horizontally by the end of the rod of the piston 13a of the cylinder 13 when it moves to the right under pneumatic control. In the position of the opening of the jaws 12 and during the steady operation of the drawing bench during actual drawing, the individual stirrup 14 can be locked automatically in the upper position of gripping head 10 by the locking element or bell crank lever 15, as shown in full lines in Fig. 2. There is an individual element 15 for each bar, which is of bent shape and can pivot about its apex 25 which is fixed on an angle or bracket 26 mounted on the die stock block 23. It is the flange 24b at the end of the upper horizontal part 24a of this locking element 15 which hooks onto the stirrup 14, while the lower vertical part of locking element or bell crank 15 is in two portions forming a knuckle joint pivoted at 20, and its extreme bottom portion or leg 19 terminates in the teat 21 while by its lateral projection 22 it bears against the die stock block 23 as shown especially in Figs. 6, 7.

The action of the locking element or bell crank 15 is supplemented by a manually operable lever 16 which is blocked during automatic operation by bell crank 15. This manually operated lever 16 can serve for starting up the machine at the time of the first drawing operation, or in case of breakdown of automatic operation.

Below the gripping jaws 12, the gripping head 10 carries three recessed pieces 27 (Fig. 3) at the bottom of whose recesses the three bars 18 lie simultaneously during the actual operation of their being drawn, after they have been inserted in the die and released from the jaws 12.

The gripping head 10 can be entirely withdrawn from its position in the sliding carriage 7 by lifting it by handles 17. This makes possible the starting into operation of the drawing bench with one, two, or three bars, according to requirements, or the complete stopping of the action of the gripping head by lifting out all the three sets of wedge jaws.

Referring to Fig. 5, the cylinders 3 and 4 for the advance and return of the horizontal sliding carriage 7, the jack 11 for raising the head 10, for gripping the bars 18, and the pneumatic cylinders 13 for causing the gripping and the release of the jaws 12 by stirrup 14, can be controlled by the means of electrically controlled valves. In Fig. 5, there is shown at 30 the electrically controlled valve for forward horizontal movement of the sliding carriage 7 with its control electro-magnet 30' actuated by relay 41, and at 31, there is shown the electrically controlled valve for the return movement of sliding carriage 7 with its control electro-magnet 31' actuated by relay 45. At 32 is shown the electrically controlled valve for the control of the raising of the head 10 by jack 11 with the corresponding control electro-magnet actuated by relay 46. The electrically controlled valve 33 is for causing, through cylinder 13, the pressing together of the jaws 12 and has a control electro-magnet 33' and the electrically controlled valve 34 is for releasing these jaws and has a control electro-magnet 34' actuated by relay 42. At 35 is shown the

high pressure pump, and 36 is the high pressure control cylinder for valves 30 and 31. 37 and 38 are shut off valves, and 39 and 40 are unions.

The apparatus which has been described operates as follows:

At the time of starting up the drawing operation and movement of the bench, with no bars 18 in place, the gripping head 10 is assumed to be in the upper position shown in Fig. 2, having been raised to that position by the jack 11, and the locking element or bell crank 15 is in closed locking position, as shown in full lines in Fig. 2. Compressed air is then sent, by manual control of valve 33 (Fig. 5), into the three cylinders 13 in the direction to cause closing of the wedge jaws 12 by action on stirrups 14, but for each one of these cylinders, this closing effect is prevented by the corresponding locking bell crank 15, since the stirrup 14, the jaws 12, and the piston 13a at this moment form an integral unit locked together by bell crank 15 by its terminal flange 24b.

The operator then feeds into place three new bars 18, which are to be drawn, inserting each of them into the wedge jaws 12 and pushing them in until the bar comes to push against the corresponding terminal teat 21 of bell crank 15. Then, the lower portion 19 of each bell crank 15 swings while bearing by projection 22 against the die stock block 23, which drives the break of the knuckle joint about its pivot 20. The upper part 24a of the bell crank 15 then pivots upwardly about the pivot 25 and, thus, its terminal flange 24b is freed from the corresponding stirrup 14. The released stirrup 14 moves to the right and immediately the wedge jaws 12 are gripped on the respective bars 18 by the displacement of the pressure piston 13a toward the right, since the cylinders are already under pneumatic pressure.

The operator then bleeds the jack 11 by manually opening valve 40 (Fig. 9), and the gripping head descends, carrying with it the bars 18 in the jaws 12. As soon as the head 10 reaches its lowest position resting on base 9 (Fig. 1), it actuates through head 11' of jack 11, a relay 41 which initiates operation of the cylinders 3 and 4, by the output of pump 1, and the bars 18 are pushed horizontally to the left toward the draw plates or dies 23a on block 23 by the forward stroke of sliding carriage 7 on which the head 10 is mounted.

When the sliding carriage 7 arrives at the end of its forward stroke in the position farthest to the left, as shown in Fig. 1, it then acts on a contact of a relay 42 which causes the sending of compressed air into the individual pneumatic cylinders 13 in the direction to cause, by displacement of stirrups 14, opening of the gripping wedge jaws 12, that is to say, their displacement to the left. At the same time, the locking elements or bell cranks 15 are automatically returned by any suitable means such as a recall spring (Figs. 6, 7) to their initial position shown in Fig. 1.

During the time of this operation, the carriage 44 of the drawing bench has been longitudinally displaced by suitable means to seize the bars 18 which have been freed by the separation of the wedge jaws 12, and it acts on a contact of a relay 45 which causes automatically the displacement of the pistons 5 and 6 of cylinders 3, 4, in the direction to cause return of the sliding carriage 7 to the right. The gripping head 10 mounted on carriage 7 returns to the position of the vertical axis of the head of jack 11. During the time of this operation, the carriage of the drawing bench has seized the bars 18 and the draw-

ing operation itself commences, and bars 18 are pulled through dies 23a.

Upon arriving at the right end of its return stroke, the sliding carriage 7, by a contact of a relay 46, causes again the lifting of the gripping head 10 by action of the jack 11, which entirely disengages the wedge jaws 12 from the bars 18 which are then in the course of being drawn. These bars then lie in the recessed pieces 27 provided below the wedge jaws 12 of head 10.

When the gripping head 10 arrives at its highest position, it locks itself in the position for holding the wedge jaws 12 open by the terminal flange 24b of the respective locking elements or bell cranks 15, latching stirrup 14.

The operating cycle of the apparatus can then recommence. However, the dropping of the jack 11 will automatically be caused as long as the drawing bench functions, since, as soon as the bars 18 which are in the course of being drawn have been released from the head upon their coming out of the draw plate or die 23a of block 23, a relay causes the operation of the jack 11 into lowered position, for example the relay 47 which is actuated by the displacement downward of the end of the one of bars 18 upon its coming out of the die.

It will be apparent to those skilled in the art that my invention may be modified or adapted to meet particular conditions, and all such modifications which are within the scope of the appended claims I consider to be comprehended within the spirit of my invention.

What is claimed is:

1. In a device for feeding metal bars into metal working apparatus, a carriage, a base comprising a track along which said carriage may be horizontally linearly displaced, said track having a first end at a metal working position, a gripping head, a vertical slide fixedly carried on said carriage and wherein said head is slidably mounted, a jack mounted on said base and having a vertically displaceable shaft, said jack being positioned so that its shaft is in register with said gripping head when said carriage is in its position at the second end of said track remote from said first end thereof, displacing means adapted to displace said carriage along said track from one end thereof to the other, gripping jaws comprised in said gripping head and adapted to grip metal bars, gripping control means for causing opening and closing of said gripping jaws, locking means adapted to hold said gripping control means in a first position to retain said jaws open, said locking means comprising terminal means positioned adjacent said first end

of said track, said locking means being so mounted that upon impact of a bar upon said terminal means said locking means releases said gripping control means from its said first position into a second position to close said jaws, and means comprising a first relay and actuating circuit and contacts therefor actuatable upon arrival of said carriage at the said first end of said track to cause said locking means to hold said gripping control means in its first position and to cause said gripping control means to open said jaws.

5 2. A device according to claim 1, and return displacement means comprising a second relay and actuating circuit and contacts therefor, said 15 means actuatable upon arrival of said carriage at the said first end of said track being arranged to actuate said return displacement means, and said return displacement means being adapted when so acted upon to cause said displacing 20 means to return said carriage to said second end of said track.

25 3. A device according to claim 1 and return displacement means comprising a second relay and actuating circuit and contacts therefor, said means actuatable upon arrival of said carriage at the said first end of said track being arranged to actuate said return displacement means, and said return displacement means being adapted when so acted upon to cause said displacing 30 means to return said carriage to said second end of said track, and means comprising a third relay and actuating circuit and contacts therefor actuatable by the arrival of said carriage at said second end of said track to cause said jack to then lift said gripping head into its elevated position.

35 4. A device according to claim 1, and means actuatable upon descent of said gripping head in said vertical slide from its upper position to its lower position to cause said displacing means 40 to displace said carriage from said second end of said track to said first end thereof.

45 5. A device according to claim 1, said locking means comprising a pivoted bell crank having an end flange on its end remote from said terminal means thereof and adapted to engage and hold said gripping control means.

J. R. TSCHUDNOWSKY.
